Application February 19, 1953, Serial No. 23,688

Term of patent 3½ years

(Cl. D92—1)

To all whom it may concern:

Be it known that I, Charles F. Scholle, a citizen of the United States, residing at Darien, in the county of Fairfield and State of Connecticut, have invented a new, original, and ornamental Design for a Textile Fabric or Similar Article, of which the following is a specification, reference being had to the accompanying drawing, forming part thereof.

In the drawing:

The single figure is a plan view of a textile fabric or similar article showing my new design.

A design unit is outlined by broken lines and is repeated as indicated.

I claim:

The ornamental design for a textile fabric or similar article, substantially as shown and described.

CHAS. F. SCHOLLE.
